WELL PRODUCTIVITY MEASUREMENT

Daniel Silverman and Ralph E. Hartline, Tulsa,
Oklahoma, assignors to Stanolind Oil and Gas Company,
Tulsa, Oklahoma, a corporation of Delaware

Application July 1, 1950, Serial No. 171,699

6 Claims. (Cl. 73—155)

1

This invention relates to fluid productivity measurements in wells producing gas, oil, or water, or mixtures of these fluids and is directed particularly to measuring the fluid productivity profile of such wells. By the term "fluid productivity profile" it is intended to designate the log of the fluid production in the producing zone of a well, as a function of depth.

Numerous methods of measuring the porosity or permeability of well formations producing gas, oil, or water have been proposed, many of which methods depend upon introducing into the well formations foreign substances, some of which can produce deleterious effects. It is well known, for instance, that fluids containing water can cause permanent damage if introduced into oil-bearing formations containing swellable clays. A further disadvantage of the porosity and permeability measurements which involve injecting fluids into the well formations is that the true ability of the formations to produce liquids into the well bore may not be ascertained because no allowance is made for the action of the driving forces which move the fluids into the well bore.

Other methods of testing well formations to determine the fluids produced have been proposed, some of which involve difficult operations, as, for example, those which depend upon the setting of one or more packers against the formation to segregate the production of one stratum from that of other formations. A drawback of those methods of productivity testing involving setting packers is that, generally, the tests are carried out with the well formations producing at rates far different from those in effect during normal well production.

It is accordingly a primary object of our invention to provide a method of well-formation productivity profiling which gives improved results because it is carried out with the well in a condition approximating normal fluid production. Another object is to provide a method of well productivity profiling which yields a complete profile at a single operation. Still another object is to provide a well productivity logging procedure which avoids injecting into the well formations fluids foreign to those produced. Still another object is to provide a well productivity measuring process which takes fully into account the driving forces involved in producing the well fluids from the various formations. Other objects, uses, and advantages of the invention will become apparent as the description proceeds.

In general, the foregoing and other objects are accomplished by a method of well productivity

profiling which comprises inserting into the fluids filling the well bore throughout the producing zone of the well an identifiable fluid or like deformable or plastic material or object which is movable, as a plug or piston, along the well bore by the well fluids as they are produced and flow along the well bore, for example, to the well tubing inlet; then causing the well formations to produce, for example, by pumping through the tubing or allowing the well to flow, the point of removal of the produced fluids being at a different level from that where the identifiable material is inserted; and then determining the variations in movement of the identifiable material as it is carried along the well bore by the produced well fluids past the various producing strata. As each stratum contributes to the stream flowing along the well bore, its presence and productivity are revealed by the changes in velocity of movement of the material.

This will be better understood by reference to the accompanying drawings forming a part of this application and illustrating certain embodiments of the invention. In these drawings:

Figure 1 shows diagrammatically in cross section a well and producing formations, with one embodiment of the invention in operation therein;

Figure 2 shows a typical record obtained, correlated in position with the formations of the well in Figure 1;

Figure 3 is a plot of velocity of the object or fluid against depth, obtainable from the chart of Figure 2;

Figure 4 shows an alternative embodiment of the invention in operation in the well of Figure 1, shown diagrammatically in cross section;

Figure 5 is a graph obtained in the operation of the embodiment of Figure 4;

Figure 6 is the velocity-depth graph obtainable from the graph of Figure 5;

Figure 7 is a diagrammatic representation, with parts in cross section, of a further embodiment of the invention; and

Figure 8 is a wiring diagram of certain parts of the apparatus shown in Figure 7.

Referring now to these drawings and, in particular, to Figure 1, a well represented generally by the numeral 11 penetrates a variety of producing formations 12, 13, and 14 separated by non-producing formations 15, 16, and 17. Well 11 is typically equipped with a casing 20 cemented in the non-producing formation 15 at the level 21 and extending to the ground surface 22. Well 11 is also provided with a production tubing 23 having an inlet 24 through which the well fluids

3

are produced to the surface 22 either by natural flow or, for example, by means of a reciprocating pump 25 of any conventional type.

In accordance with our invention, the relative productivity of formations 12, 13, and 14 and their location in the producing zone of well 11 are determined by first introducing into the well bore a plastic or deformable mass or body 30 of material which is identifiable in the presence of, and of about the same specific gravity as, the well fluids 31 normally filling the bore of well 11. Typically, the material 30 may comprise a stable emulsion of oil and water or an oil-base gel formed by a mixture of crude or refined oil with such bodying agents as the alkali metal salts of long-chain fatty acids or mixtures thereof. One example of such agents is the mixture of hydroxy aluminum stearate, palmitate, and oleate sold commercially under the trade name Napalm. Preferably, the body 30 also forms a definite interface 32 with the well fluids 31, which interface is detectable with a pair of electrodes 33 and 34; but this is not strictly essential, as material 30 may also comprise a quantity of miscible liquid, such as water, differing substantially in salinity or other properties from the well water and miscible therewith. If the length of producing zone to be surveyed is limited, the main body of identifiable fluid can still be followed even though some intermingling occurs with the well fluids.

The amount of material in or volume of the well bore occupied by the body 30 is not critical, but it should ordinarily be sufficient to fill the well bore for a length at least equal to the well diameter. It can, of course, be and preferably is several times this amount, a length of five or ten feet being entirely practical, particularly if the length of well bore to be explored is considerable.

One manner of introducing the deformable or fluid body 30 close to the bottom of the well bore 11 is by means of a conventional dump bailer 37 lowered from surface 22 on a wire line 38, preferably containing at least one insulated conductor and being wound on a reel 39 at the surface. The electrodes 33 and 34 are mounted in an exposed position on the outside of bailer 37. Through the insulated conductor of cable 38, one of the electrodes 33 or 34 is connected in series with an indicator or recording meter 40 and a generator or battery 41, the other terminal of which battery is connected to the ground surface 22 at point 42. The other one of the electrodes 33 or 34 is similarly grounded in the well 11 to the body of bailer 37.

Bailer 37 having been lowered through the annular space 43 between tubing 23 and casing 20 and the mass of emulsion or gel 30 having been deposited near the bottom of well 11, production of fluid from the well formations is started by operating pump 25 and withdrawing well fluids through the tubing 23. It will be noted in Figure 1 that the tubing inlet 24 is located at the opposite end of the producing zone of well 11 from the body 30. Accordingly, when pump 25 is operated and the well formations produce into the well bore, the general movement of fluids in the well bore is that indicated by the arrows 44, and the body 30 is swept along in the direction of the movement of fluids by production from the stratum 14. Simultaneously, an operator at the surface 22 observing the meter 40 is able to determine when the electrodes 33 and 34 are located at the interface 32 between the body 30 and well fluids 31, and he is then able to regulate the up-

ward motion of the electrodes and bailer 37 by reeling in the cable 38 in a manner to follow the movement of body 30. Upon recording with conventional means, the depth of electrodes 33 and 34 on a chart moved in accordance with time, a graph is obtained such as that shown in Figure 2.

Knowing the position of the body 30 as a function of time, assuming, of course, that the production rate of the well is constant or is known with sufficient accuracy to make appropriate corrections and that the diameter of the well bore is reasonably uniform, it is a simple matter to obtain or compute the graph of Figure 3 which shows the velocity of movement of body 30 as a function of depth. This is an idealized plot to illustrate the principles of the invention, but it will be observed that the velocity of the body 30 increases over the producing interval 14, reaching a constant value of V_1 which continues throughout the non-producing stratum 17. Upon reaching the producing stratum 13, a second change in velocity occurs from V_1 to V_2 , and the body 30 then subsequently moves with uniform velocity through the non-producing interval 16. A third increase in velocity occurs as the body 30 passes the producing stratum 12 and levels off to the value V_3 opposite the non-producing stratum 15. From such a plot as Figure 3, it is a simple matter to obtain both the location in depth of the producing strata—those locations being identified by the regions where the velocity of the body 30 is changing—as well as the relative productivities of these strata, which is proportional to the relative magnitudes of the changes in velocity. As all of this information is obtained with the well producing its normal fluids in normal quantity from the formations, there is no possibility of error due to varying permeability of the formations to fluids foreign to those naturally produced. Consequently, such a plot as Figure 3 is an accurate indication of the true well productivity profile.

If the production rate of the well is not constant, but varies in a known way throughout the period of measurement, then there is superimposed on the velocities shown in Figure 3 a varying velocity which must be accounted for or subtracted off the observed or computed values to arrive at the true velocity-depth profile. Likewise, if the well diameter is not uniform, but is known from previous caliper measurements, for example, its effect in producing apparent changes in velocity must be considered. The apparent interface velocity varies inversely as the cross-sectional area of the well bore (and thus inversely as the diameter squared) regardless of whether the interface is opposite a producing or a non-producing formation. Consequently, the effect of known diameter variations should always be evaluated and removed before the resulting interface velocity-depth log is interpreted in terms of formation productivity.

By interpreting the foregoing data in conjunction with surveys to determine the nature of the various fluids produced by the strata outlined in Figure 3, it is possible to determine both the productivity and the identity of the fluids produced by the strata 12, 13, and 14.

In Figure 4 is shown an embodiment of the invention capable of being carried out chiefly by operations performed at the ground surface 22. In this embodiment, the material 30 is merely introduced from the ground surface 22 by pouring it into the annular space 43 and

allowing it to fall into the well fluids 31. If desired or necessary, additional well fluids 50 may be poured back into the annular space 43 on top of the body 30 to cause it to move downwardly, at least until it reaches the top producing stratum 12. Pump 25 is operated in the meantime with the tubing inlet 24 set as close as possible to the well bottom. Consequently, the arrows 44 indicating the general direction of fluid movement point downwardly, and the body 30 with interface 32 similarly moves in the direction of the pump inlet. As in Figure 1, this interface 32 is followed by the electrodes 33 and 34 which may be mounted on a simple electrode carrier 51 instead of the large bailer 37. By moving them in synchronism with the interface 32, as observed by the indications of meter 40, the operator reeling out the cable 38 from the reel 39 is able to obtain in the plot of the depth of body 30 as a function of time shown in Figure 5.

Figure 5, it will be recognized, is analogous to Figure 2, except that the reversal of direction of fluid movement has inverted from top to bottom the graph showing the depth of body 30 as a function of time.

The plot of velocity as a function of depth, shown in Figure 6, is in all ways analogous to that shown in Figure 3 and explained in connection with that figure. As before, the zones 12 and 13 are delineated by the depth intervals over which velocities change from V_1 to V_2 , and from V_2 to V_3 , and the relative magnitudes of these velocity changes are the indications of the relative formation productivities.

In this particular illustration the velocity change V_3 to V_4 is an indication of only that part of formation 14 producing above the level of pump inlet 24, since the position of this inlet determines the bottom limit of investigation possible with this embodiment of the invention. The top of formation 14, however, is clearly marked by the point of the curve where the velocity begins to increase above the constant value V_3 . The relative magnitudes of the observed velocity changes indicate relative formation productivities, as far as they go.

An obvious advantage of this embodiment over that shown in Figure 1 is that the equipment lowered in annular space 43 is considerably simpler, and the rate of production from the formations of well 11 can be readily regulated by the rate of introducing an additional fluid 50 into the annular space 43, relative to the pumping rate through tubing 24. That is, after a period of constantly pumping the well 11 through tubing 24 at a given rate and constantly introducing liquid 50 at a somewhat lesser rate down annular space 43, a producing condition is reached in which the well formations 12, 13, and 14 contribute fluids at a rate just sufficient to make up the difference between the rate of introduction of fluid 50 and the rate of removal of fluids by pump 25. Thereafter, the three rates—introduction, production, and pumping—remain substantially constant, or, in other words, a producing equilibrium exists. For example, by making the rate of introduction of fluid 50 one-half of the rate of removal of fluid by the pump 25, the well formations 12, 13, and 14, when equilibrium conditions are reached, will then produce at one-half of their normal rates. An additional control on the rate of production of the well formations is thus provided.

A further embodiment of our invention is that shown in Figure 7 in which there is lowered in-

to the annular space 43 of well 11 apparatus comprising a plurality of umbrella packers or baffles 60, 61, and 62. These are run into well 11 in a closed position on a tubular member 63 loosely coupled to the bottom of dump bailer 37 containing a highly viscous material such as an oil-and-water emulsion or an oil-base gel. Upon reaching the bottom of well 11, a rod 64 is actuated to release the gel into the tubular member 63 and to expand the packers 60, 61, and 62 into contact with the well wall. Through the tube 63 and suitable ports therein, the gel 65 then fills the space between and around the expanded flexible packers and thus helps to prevent well fluids from by-passing them. Consequently, producing of the well 11 by the pump 25 with the inlet 24 set above the producing zone causes movement of the gel and packers as a unit upwardly in the well, which movement is preferably detected by a moving contactor 66 attached to the rod 64 fixed to the bailer 37 which operates between a pair of electrical contacts 67 and 68 fixed to the tubular member 63 and thus moving with the packers 60, 61, and 62.

The electrical circuit of this arrangement is shown in Figure 8, resistors 70 and 71 of different value respectively in series with the contacts 68 and 67 serving to identify by different values of current flow to an operator at the surface 22 observing meter 46 which of the contacts 67 or 68 is closed with the moving contactor 66. The operator is thus able to follow the upward movement of the packers and gel by reeling in the cable 38 on the reel 39 without imposing any appreciable force on the packer structure.

It will be understood that this embodiment of the invention gives a plot of deformable plug position as a function of time in passing the producing formations 12, 13, and 14, which is, in all respects, similar to that of Figure 2. However, uncertainties as to the possible relative movement of the fluid column as a whole and the gel body 30 are reduced in this embodiment which, even more than in the previous embodiments, moves along the well bore like a flexible piston.

Although the embodiments described thus far have made use of artificial interfaces established in the well bore and moved therealong by production from the formations, similar results are sometimes obtainable by observing the motion of natural interfaces, such as the natural oil-water interface, in wells where such exist. Also, it is not always necessary to remove well fluids to cause movement of an interface along the well bore. For example, a natural or artificial interface in the embodiment of Figure 4 could be made to move upwardly from near the pump inlet 24 simply by stopping the pump, while the well formations continue producing at a decreasing rate until static equilibrium is reached. Anomalous movements of this interface are observed as it passes the formations 13 and 12 in moving upwardly.

There are, also, conditions under which no movement of an interface is significant. Thus, after a period of steady production of the well 11, a condition of producing equilibrium is reached with no further downward movement of the annulus fluid column above the top producing formation 12. Upon then establishing a plurality of successively lower interfaces in this column and noting whether they move or not, the top of formation 12 is accurately delineated at that depth where the established interface can first be observed to move. Following this inter-

face from there on down the well gives the desired productivity profile.

While our invention has been described with reference to certain particular embodiments and explained by idealized diagrams of the results obtained, it is to be understood that these are for purposes of illustration only, and that modifications thereof will occur to those skilled in the art. The scope of our invention, therefore, should not be considered as limited strictly to the described embodiments but is to be ascertained from the scope of the appended claims.

We claim:

1. The method of measuring the productivity profile of a well which comprises establishing in the fluids in the well bore in the vicinity of the producing zone of said well an identifiable liquid barrier body movable as a unit by the well fluids as they flow along said well bore, removing well fluids from said well bore at a different level from that where said body was established to cause production of additional fluids from the well formations into the well bore, and following the movement of said body to determine the variations in said movement as said body passes strata producing into the well bore.

2. The method of locating at least one stratum producing fluids into a well bore which comprises establishing in the fluids in the well bore at a depth different from said stratum a barrier body of identifiable material movable as a unit by the well fluids as they flow along said well bore and forming two observable interfaces with the well fluids respectively above and below said body, producing fluids from the formations into said well bore to cause movement of said body past said stratum, and following the movement of said body by observing at least one of said interfaces to determine variations in said movement as said body passes said stratum.

3. The method of measuring the productivity profile of a well which comprises inserting into

5 the well-bore fluids near one boundary of the well producing zone a barrier body of identifiable liquid material movable as a unit by the flow of fluids along the well bore and forming two observable interfaces with the well fluids respectively above and below said body, removing fluids from said well bore near the other boundary of said zone to cause fluid flow from the formations into the well bore and movement of said fluids and body along said well bore, and following the movement of said body by observing at least one of said interfaces to determine variations in said movement as said body passes producing strata in said zone.

10 4. The method of claim 3 in which said body is inserted near the upper boundary of the well producing zone and fluids are removed from near the bottom of said well bore.

20 5. The method of claim 4 including the further step of introducing from the surface additional liquid into the well annulus on top of the well fluids therein, to cause said body to move downwardly through said zone.

25 6. The method of claim 3 in which said body is introduced into the well fluids near the bottom of the well bore and fluids are removed from said bore at a point above the top of the producing zone.
